UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

CAP FOR LAMP-SOCKETS, PENDANT-SWITCHES, AND OTHER ELECTRICAL DEVICES.

1,121,374.

Specification of Letters Patent. Patented Dec. 15, 1914.

Application filed April 8, 1912. Serial No. 689,289.

To all whom it may concern:

Be it known that I, CHARLES J. KLEIN, a citizen of the United States, residing at Milwaukee, in the county of Milwaukee and State of Wisconsin, have invented new and useful Improvements in Caps for Lamp-Sockets, Pendant-Switches, and other Electrical Devices, of which the following is a full, clear, concise, and exact description, reference being had to the accompanying drawing, forming a part of this specification.

My invention relates to caps for lamp sockets, pendant switches and other electrical devices.

It has among its objects to provide a cap with lining retaining means which serve to hold the lining securely in position and yet permit the same to be readily inserted or removed.

Other objects and advantages of my invention will hereinafter appear.

In order to more fully disclose my invention, I shall describe the embodiments thereof shown in the accompanying drawings. It should be understood however, that the forms shown are susceptible of modification.

In these drawings: Figure 1 is a vertical sectional view through one form of cap. Fig. 2 is a bottom plan view of Fig. 1. Fig. 3 is a bottom plan view of one portion of the cap shown in Figs. 1 and 2 having one of the lining retaining members in position therein. Fig. 4 is a partial sectional view of the parts at right angles to Fig. 1. Fig. 5 is a perspective view of the insulating lining. Fig. 6 is a vertical sectional view through a modified form of cap. Fig. 7 is a bottom plan view of the dome member of the cap with the lining retaining means positioned thereon. Fig. 8 is a sectional view on line 8—8 of Fig. 7. Fig. 9 is a perspective view of a modified form of the lining retaining means shown in Figs. 6, 7, and 8. Fig. 10 is a vertical sectional view through another form of cap. Fig. 11 is a transverse sectional view on line 11—11 of Fig. 10.

I shall first describe that form of my in-

vention shown in Figs. 1 to 4. The cap is 50 provided with a dome shaped portion 1 having two yielding strips 2 located therein on opposite sides of the cap and holding an insulating lining 3 in position within the same. The strips 2 extend across the 55 interior of the cap in chord like relation with respect thereto and are preferably connected at both ends to the same. These strips are preferably formed of punchings of thin resilient metal or resilient wire. In 60 these figures I have shown a cap of the construction described and claimed in my co-pending application, Serial No. 660,345, filed November 15th, 1911, wherein the dome-shaped member of the cap is provided with 65 an annular flange 4 over which is spun a depending rim 5 arranged to fit over the socket shell. In such a construction, in order to provide a sturdy support, I preferably clamp the ends of the resilient lining 70 retaining strips 2 between the flange 4 and the rim 5. In order to hold the retaining means snugly in position and to assist in the process of assembling them, I preferably provide the strips 2 with enlarged or bent-over ends 6 which snap over the flange 4 in notched or cut-away portions 7 in the same. (Figs. 3 and 4.) When the dome-shaped member 1 and rim 5 are secured together as by the spinning on of the rim to 80 the flange 4, the resilient supports 2 are very securely and snugly held in position in such a manner as to provide exceedingly sturdy supports for the lining. (Fig. 4.) In order that the yielding supports 2 may 85 have sufficient play, I preferably provide the lower surface of the flange 4 with grooves 8 connecting the cut-away portions 7. (See Fig. 3.)

By the provision of the resilient supports 90 or strips the lining may be inserted in the cap by simply forcing it between the strips which then recede into the grooves 8 and after the passage of the lining into the cap snap out to the position shown in Fig. 1. 95 It is to be noted that in this position each strip supports the insulating lining at two peripheral points and underlies the lining

between these points, thereby firmly securing the lining in place and obviating all danger of its accidental displacement. To remove the lining it is only necessary to exert a lateral pressure upon one of the strips to bow the same out of the path of the lining, after which the lining may be readily withdrawn. The bowing of the strip may be readily accomplished by inserting a thin instrument or the thumb nail between the lining and the cap and then moving the same around the periphery of the lining against the yielding strip. To facilitate the insertion and removal of the lining the strips may be slightly bowed if desired before inserting them in the cap. Due to the provision of my yielding retaining means the lining used may be entirely plain and of the simplest construction (Fig. 5) and be inserted when in any desired position with respect to the retaining means. If desired the lining may be rigid or stiff. It is, of course, evident that instead of using a plurality of resilient strips one of the strips might be rigid; the operation of inserting or removing a lining remaining substantially the same as that heretofore described.

In Figs. 6, 7 and 8 I have illustrated the resilient strips 2 formed in one piece and connected by arc-shaped strips 9 at their ends. These strips 9 are preferably flat as shown in Fig. 7 and the resilient supports 2 are preferably formed from the same by twisting the strips near their ends as at 10 in order to give the supports the desired strength and lateral flexibility. In order to hold the strips 9 securely in position they are preferably clamped between the two parts 1 and 5 of the cap as shown in Fig. 8. It is evident that upon the insertion and removal of the lining the operation and function of the retaining means is the same as that heretofore described in connection with Figs. 1 to 4. As heretofore described, this form of retaining means may likewise, if desired, be made of either a punching of thin metal as shown in Fig. 7, or of a spring wire as shown in Fig. 9.

Figs. 10 and 11 show a single piece cap provided with resilient lining supporting members 2, the ends of which extend through openings in the sides of the cap and are bent back upon the exterior of the cap as at 11 in order to hold them securely in position.

It will be understood that the forms of my invention shown herein are several embodiments of my inventive idea and that I have not attempted to describe all of the various modifications of the same which may be adopted without departing from its spirit.

What I claim as new and desire to secure by Letters Patent is as follows:

1. A casing cap provided with a lining retaining member having a yieldable portion normally disposed in a chord-like relation to the cap wall and movable toward the same.

2. In combination, a casing cap, an insulating lining adapted to snugly fit the interior thereof, and a transversely extending resilient member carried by said cap and laterally and outwardly yieldable to permit the insertion and removal of said lining.

3. In combination, a casing cap, an insulating lining adapted to snugly fit the interior thereof, a transversely extending resilient member carried by said cap and laterally and outwardly yieldable to permit the insertion of said lining and to snap therebeneath for supporting the same.

4. In combination, a cap, an insulating lining therein, and a retaining member having a portion engaging said cap and a portion spaced from said cap for supporting said insulating lining, said last-mentioned portion of said retaining member being yieldable toward the wall of said cap to permit the removal of said lining.

5. In combination, a casing cap, an insulating lining snugly inclosed therein, and a retaining member for said lining permanently secured to said cap and having a resilient portion spaced from the interior wall thereof and underlying said lining.

6. In combination, a casing cap, an insulating lining closely fitting the interior thereof, and a retaining strip fixed to said cap beneath the margin of said lining and having a resilient portion spaced from the wall of said cap and engaging the edge of said lining.

7. In combination, a casing cap, an insulating lining therein, and means carried by said cap and underlying said lining for supporting the latter, said means being yieldable away from said lining whereby the latter may be removed from said cap independently of the removal of said means.

8. In combination, a casing cap, an insulating lining closely fitting the interior thereof, and a retaining member for said lining carried within said cap, said member being yieldable away from said lining whereby the latter may be removed from said cap independently of the removal of said member.

9. A cap having a transversely extending lining retaining member, said cap being formed in sections and said member being clamped between said sections.

10. The combination of a two part cap comprising a dome member and a shell engaging member formed separately and se-

- cured thereto, and one or more lining retaining members having the extremities thereof clamped between said parts of said cap.
- 5 11. A cap having a resilient lining retaining strip extending transversely thereof, said cap being formed in sections and said strip having its opposite ends clamped between said sections.
- 10 12. A cap having therein a plurality of lining retaining members extending transversely thereof, one of said members being laterally yielding.
- In witness whereof, I have hereunto subscribed my name in the presence of two witnesses. 11
